DISPLAY CONTAINER FOR PEN AND PENCIL SET

Samuel Braun, Rye, N.Y., assignor to B.C.N. Design Products Inc., Middle Village, N.Y., a corporation of New York

Filed Oct. 2, 1962, Ser. No. 71,977

Term of patent 14 years

(Cl. D58—12)

FIG. 1

FIG. 2

FIG. 3

FIG. 4

FIG. 5

FIG. 1 is a top front perspective view of a display container for pen and pencil set, showing my new design, in closed condition;

FIG. 2 is a top front perspective view thereof in open condition;

FIG. 3 is a bottom rear perspective view thereof in closed condition;

FIG. 4 is a front elevational view thereof; and

FIG. 5 is a left-side elevational view thereof.

I claim:

The ornamental design for a display container for pen and pencil set, as shown.
